(57) **CLAIM**

The ornamental design for a dual rod corner retractor clamp, substantially as shown and described.

DESCRIPTION

FIG. 1 is a perspective view of a dual rod corner retractor clamp showing our new design, the broken line showing is for illustrative purposes only and forms no part of the claimed design.

FIG. 2 is a front elevational view thereof.

FIG. 3 is a right elevational view thereof.

FIG. 4 is a rear elevational view thereof.

FIG. 5 is a left elevational view thereof.

FIG. 6 is a top plan view thereof; and,

FIG. 7 is a bottom plan view thereof.
